[57] CLAIM

The ornamental design for a set of chesspieces, as shown and described.

DESCRIPTION

FIG. 1 is a top plan view of a set of chesspieces according to a first embodiment of the invention showing, from left to right, Pawn, Rook, Knight, Bishop, King and Queen;

FIG. 2 is an elevation view of a set of chesspieces shown in FIG. 1;

FIG. 3 is a top plan view of a set of chesspieces according to a second embodiment of the invention showing, from left to right, Pawn, Rook, Knight, Bishop, King and Queen;

FIG. 4 is an elevation view of the set of chesspieces shown in FIG. 3;

FIG. 5 is an orthographic projection of the chesspieces of FIGS. 1-4, shown in their starting places on a chessboard shown in broken lines for illustrative purposes only.

FIG. 1

FIG. 2

FIG. 3

FIG. 4

FIG. 5
